CLAIM

The ornamental design for golf club head, as shown and described.

DESCRIPTION

FIG. 1 is a perspective bottom plan view of our new design for a golf club head;

FIG. 2 is a bottom plan view thereof;

FIG. 3 is a top plan view thereof;

FIG. 4 is a heel end view thereof;

FIG. 5 is a toe end view thereof;

FIG. 6 is a front elevation view thereof; and,

FIG. 7 is a rear elevation view thereof.

The broken lines shown are included for the purpose of illustrating unclaimed subject matter and form no part of the claimed design.
